CLAIM

The ornamental design for a grill brush pad, as shown and described.

DESCRIPTION

FIG. 1 is a top perspective view of a grill brush pad of the present invention;

FIG. 2 is a top view thereof;

FIG. 3 is a left side view, the right side being a mirror image thereof;

FIG. 4 is a front side view, the back side being a mirror image thereof;

FIG. 5 is a top perspective view of the grill brush pad in an alternative environment;

FIG. 6 is a left side view thereof, the right side being a mirror image thereof;

FIG. 7 is a top view thereof;

FIG. 8 is a front view thereof; and,

FIG. 9 is a back view thereof.

The broken lines showing environmental structure are for illustrative purposes only and form no part of the claimed design.

1 Claim, 6 Drawing Sheets
